UNITED STATES PATENT OFFICE.

KENNETH ROSS, OF BONNER, MONTANA.

STAKE-POCKET.

1,218,957.

Specification of Letters Patent. Patented Mar. 13, 1917.

Application filed December 1, 1916. Serial No. 134,339.

To all whom it may concern:

Be it known that I, KENNETH ROSS, a citizen of the United States, residing at Bonner, in the county of Missoula and State of Montana, have invented certain new and useful

Improvements in Stake-Pockets, of which the following is a full, clear, and exact description, reference being had to the accompanying drawings, forming a part hereof.

My invention has relation to improvements in stake-pockets; and it consists in the novel features of construction more fully set forth in the specification and pointed out in the claims.

The present improvement is directed to car-stake pockets, the main object sought being to provide a pocket which will effectively hold the stakes in an upright position and thus prevent the load from spreading at the top, such spreading as is well known, interfering with the movement of the load through tunnels and Howe truss bridges. A further object is to entirely relieve the bunks or cross members supporting the load from any longitudinal strain by the elimination of any positive connection between the pocket and the end of the bunk. In the present embodiment of my invention special provision is made for permanently maintaining the axis of the pocket in a vertical plane so that the stake will remain in the same plane while in service. The present stake-pocket and the means by which the same is secured to the side of the car present mechanical advantages over prevailing forms of stake-pockets and stake-holders, these advantages being fully apparent from the following detailed description of the invention in connection with the accompanying drawings, in which—

Figure 1 represents a side elevation of the platform of a freight car such as used for transporting logs showing my invention applied thereto; Fig. 2 is a vertical cross-section on the line 2—2 of Fig. 1; Fig. 3 is a top plan of the stake-pocket; Fig. 4 is a side elevation thereof with side sill of the car in cross-section; Fig. 5 is a front elevation of the pocket, parts being removed; Fig. 6 is a vertical cross-section on the line 6—6 of Fig. 3, showing in addition the end of the bunk in side elevation; Fig. 7 is a vertical cross-sectional detail on the line 7—7 of Fig. 6; Fig. 8 is an enlarged side elevational detail of the locking latch and tripper with part of the pocket wall in section; Fig. 9

is a side elevation of the locking latch; Fig. 10 is an inner edge view of the same; Fig. 11 is a side elevation of the tripper for the latch; and Fig. 12 is an inner edge view thereof.

Referring to the drawing, 1, represents the side sill of the platform or frame of a car, said sill in the present embodiment of my invention being a structural member in the form of a flanged plate or channel beam, although I do not wish to be understood as limiting myself to any particular cross section of side sill or the material of which the same is constructed or composed. Bolted to the side sill 1 is the pocket-body or casting 2 on the outer face of which is formed the substantially semi-cylindrical pocket formation or depression *d* having the bottom sloping bounding edges *e*, *e*, as shown. The upper portions of the side edges of said depression are recessed to a suitable depth leaving shoulders *s* for the support of the terminals of the substantially semi-cylindrical cap-piece 3 operating as a complementary member to the pocket-body, and forming with the concave walls of the depression *d* an opening or passage-way *O* whose walls entirely surround the stake *S* inserted thereinto. On one side, the cap 3 is provided with a centrally disposed perforated ear or lug 4 to which is coupled one end of a link 5, the opposite end of the link being connected to a U-bolt 6 whose arms are passed through openings *o*, *o*, in the adjacent side of the pocket-body 2 (Fig. 5), the nuts *n* securing said bolt to the body. On the opposite side, the cap 3 is provided with a centrally disposed lug or ear 4' having an elongated slot *h* which is freely traversable by a U-shaped clevis 7 the free ends of whose arms are connected by a pin 8 to which is pivotally secured between said arms one end of a latch or hook 9 operating freely in the vertically elongated slot or opening *t* of the pocket-body or plate 2. The free end of the latch is provided with a locking head *m* which, when the latch is in its depressed or locking position engages the plate 2 below the bottom of the slot *t*, said plate serving as a keeper for the latch (Fig. 8). The latch may be disengaged from the plate 2 by means of a tripper 10 pivoted at one end to a headed stud or pin 11 on the adjacent side wall of a rear cavity or receptacle 12 by which the end of the cross timber or car bunk 13 is received. The tripper 10 in shape resembles a bell-crank

100

105

110

lever, oscillating about the axis of the stud 11, one arm of the bell-crank being in the form of a finger *a* above which is formed a cavity *c* (Fig. 11) which receives the free end of the latch, the finger being in permanent engagement with the locking head *m* of the latch. To the eye *e'* of the other lever arm may be attached a cord or chain (not shown) for operating the tripper. When 10 the latter is oscillated to the dotted position indicated in Fig. 8, the latch will be raised to its unlocked or released position, and may be withdrawn from the slot *t* by moving the clevis 7 outwardly along the slot *h* of the 15 lug or ear 4'. In this manner one side or end of the cap 3 may be readily uncoupled from the body 2 and swung outwardly (about the U-bolt 6 as an axis) whenever occasion arises to remove a stake (dotted position Fig. 3). When the latch 9 is down, the tripper 10 serves the purpose of a lock, preventing accidental displacement or movement of the latch which cannot be raised without an upward oscillation of the finger *a*, 20 because confined by the walls of the cavity *c*, (Fig. 8).

As was pointed out above, the pocket-body is secured to the side sills 1 of the car. In the present embodiment of my invention the body or plate 2 is bolted to the side sill, the plate being provided with bolt holes *o'* to receive the bolts 14, and with holes *o''* to receive the threaded ends of the arms of the U-bolt or strap 15 which passes around the 25 lower terminal of the stake. The upper portion of the pocket-body (opposite the bottom of the cavity 12) is provided with openings *i*, *i*, for receiving the terminals of the cross tie-rods 16, by which the members of each 30 pair of pocket bodies disposed opposite one another on the sides of the car are tied together. It is to be understood of course that for every pocket-body on one side of the car there is a corresponding pocket-body on the 35 opposite side, the two being tied together by the tension members or rods 16. The tie rods are disposed in pairs, with one rod on each side of a bunk 13, the terminals of the bunks being received in the cavities or pockets 12 of the oppositely placed pocket-bodies 2, a bunk being thus confined between two tie-rods (Fig. 3). The pocket formations or 40 cavities 12 rest directly on the upper flanges of the sills 1, the tie-rods 16 connecting opposite pocket-bodies being raised slightly above the side sills or platform of which they form a part, and serving not only as ties between opposing pocket-bodies, but as means for relieving the strain on the car 45 sills. Thus the cross rods 16 serve the double function of keeping the pockets in place and of tying the sills. The sides and bottom of the terminals of the bunks received by the 50 cavities or bunk-pockets 12 are recessed or rabbeted so as to be snugly received by the

cavity, the bottom recess being of a depth to bring the lower face of the bunk in the plane of the bottom face of the cavity (Fig. 6). The walls of the cavities 12 are sufficiently deep to protect the ends of the bunk dropped thereinto, and when the bunks are once in place in the cavities they require no bolting, since, under my improvement the bunks are not required to take care of any portion of the strain imposed by the load on the stakes 55 S and pocket-bodies 2.

Without the complementary member 3 the depression or semi-cylindrical formation *d* can scarcely be considered as a pocket; and it may accordingly be assumed that said complementary member enters into the construction of the stake-pocket proper. In the present embodiment of my invention the passage *O* formed by the inner walls of the member 3 and of the depression *d* is cylindrical, that is to say circular in cross-section; but I desire it to be understood that I need not adhere to this particular cross-section and any other form of cross-section, such as elliptical, polygonal and the like comes 60 within the scope of my invention. Of course the holder or support for the stake S is not complete without the U-bolt 15; and while this bolt is not strictly a part of the pocket it co-operates with the pocket proper so as to rigidly hold the bottom of the stake against movement, the nuts *n'* on the screw-threaded terminals of the bolt arms making it possible to adjust the available opening through the bolt so as to grip the stake with any degree of firmness desired. The stake-pocket proper may be said to be without a bottom, or to have an open bottom, such open bottom allowing the stake to be driven into the 65 pocket to firmly hug the pocket walls, and the walls of the loop formed by the U-bolt. Especially is the open pocket desirable in cases where the stakes become seasoned and loose in the pockets while in use. The open bottoms of the pockets permit the loosened stakes to be driven and wedged in more deeply into the pockets, thereby giving excellent service. In addition the adjustable U-bolt 15 may be positioned to grip the lower end of the stake with any degree of 70 firmness. In practice of course it is to be understood that before a stake is driven into its pocket, the member 3 is first swung to closed position and locked by the latch 9 to the plate 2 (as a keeper), the tripper 10 being oscillated to lock the latch against disengagement from said plate as previously described. The U-bolt 15 may be set to proper position to grip the stake while the latter is being driven into its pocket, or be 75 passed about and caused to grip the lower end of the stake after the stake has been 120 fully inserted into the pocket.

For convenience, we may consider the cavity or receptacle 12 which receives the 125

end of the car bunk 13 as a "pocket;" so that it would follow that the casting or pocket-body 2 is provided with two pockets, one for receiving a stake, and the other for receiving the end of the bunk, the pockets being on opposite sides of the casting and opposite one another. As previously pointed out, the present construction prevents the load from spreading at the top by maintaining the stakes permanently in an upright position or in truly vertical planes. This is made possible by the tie rods 16, their position being such as to effectively resist the outward thrust of the load against the stakes. Under this thrust the plates 2 would naturally tend to oscillate away from the sills 1 about fulcrums located in the region of the U-bolts 15; but the tie-rods 16 are positioned high enough (being above the sills 1) to take up and resist this thrust and thereby maintain the plates and the axes of the stake-pockets in vertical planes, the plates being held in permanent rigid connection with the sills 1 to which the outward thrust aforesaid is communicated, no part of this strain or thrust being however communicated to the bunks 13 which support the logs or load. The axes of the stake-pockets being thus maintained in vertical planes it follows that the stakes driven into them will remain in an upright position thereby preventing the load from spreading at the top. The construction here shown need not of course be adhered to and changes within the purview of the skilled mechanic might be resorted to without departing from the nature or spirit of the invention. Features shown but not specifically alluded to are well understood in the art and require no description in the present connection.

Having described my invention what I claim is—

1. A member provided with a stake-pocket, means for securing the member to the body of a car, and a tie or tension rod leading from the member to a corresponding member placed in opposed relation thereto for connecting the members and thereby maintaining the axes of the pockets of the respective members in vertical positions.

2. A member provided with a stake-pocket, and with a bunk pocket partitioned therefrom.

3. A member provided with a stake-pocket on one side and with a bunk pocket partitioned therefrom on the opposite side.

4. A member provided with a stake-pocket on one side and with a bunk pocket on the opposite side opposite to and partitioned from the stake-pocket.

5. A pocket-body provided with a depression on one side, a movable complementary member secured to the pocket-body and operating with the walls of said depression to form an open-bottomed stake-pocket, and

a member positioned below the pocket for holding the lower end of the stake inserted into the pocket.

6. A pocket-body provided with a depression on one side, a movable complementary member secured to the pocket-body and operating with the walls of said depression to form a pocket for receiving a stake, and a suitable formation on the pocket-body opposite the complementary member for receiving the end of a car bunk.

7. In combination with the side members of a car platform, a pocket-body secured to each side member on opposite sides of the car and projecting a suitable distance above said side member, means for securing the pocket-bodies to the side members at points below the upper edges of said members, tie members spanning the platform and connecting the pocket-bodies at points above the upper edges of the side members of the car, and stake-pockets on said pocket members.

8. In combination with the side sills of a car platform, a pocket-body secured to each sill on opposite sides of the car and projecting a suitable distance above said sill, means for securing the pocket-bodies to the sills at points below the upper edges of the sills, a stake-pocket on the outer face of each pocket-body, an inwardly projecting bunk pocket opposite the stake-pocket positioned above the upper edge of the sill, and tension members on opposite sides of the bunk-pockets for connecting or tying together the oppositely disposed pocket-bodies.

9. A pocket-body or plate provided on one side with a concaved depression, a complementary substantially semi-cylindrical member linked at one end to the plate on one side of the depression aforesaid and operating to form with the walls of said depression an open bottomed pocket for receiving a stake, a latch linked to the opposite end of said member and operating through an opening of the plate, and a tripper member on the plate for operating the latch.

10. In a pocket-body, a stake-pocket provided with a cap forming a detachable section of the pocket wall, a latch linked to one end of the cap and passing loosely through the wall of the pocket-body, a locking-head terminating the free end of the latch and engaging the wall of the pocket-body for a locked position of the latch, a tripping lever provided with a cavity for receiving the free end of the latch and having a finger or arm engaging the locking head of the latch, whereby upon an oscillation of the tripping lever in a given direction the finger actuates the latch and releases the locking head thereof from engagement with the wall of the pocket-body.

11. In combination with a pocket-body provided with a centrally disposed depres-

sion, a U-bolt carried by the pocket-body on one side of the depression, a semi-cylindrical cap linked at one end to the U-bolt and adapted to swing in a plane transverse to the axis of the depression, a slotted ear on the opposite end of the cap, a clevis operating in the slot of said ear, a latch hinged to the clevis and free to operate through the pocket-body, and a locking tripper member hinged to the pocket-body for controlling the latch.

12. A stake-pocket comprising a plate provided on one side with a semi-cylindrical vertically disposed depression, a semi-cylindrical cap linked at one end to the plate and operating when swung to closed position to form with the upper portion of said depression a cylindrical passage or open-bottomed stake-pocket, means for locking the free end 20 of the cap to the plate, and a U-bolt positioned below the pocket thus formed to receive the bottom terminal of the stake inserted into the pocket.

13. A pocket-body provided with a stake-pocket on one side, said pocket having a movable section operating to release the stake with a movement of the section in one direction, a bunk pocket on the opposite side of the pocket-body, a latch carried by the 30 movable section of the stake-pocket and operating through the pocket-body, and a tripper pivoted to the wall of the bunk pocket for controlling the latch.

14. In combination with the side sills of a car frame, pocket-bodies secured to the outer faces of the sills and disposed opposite one another, means for securing the pocket-bodies to the sills, and tension members disposed across the car above the sills and connecting the upper portions of the respective pocket-bodies for holding the pocket-bodies against spreading and thereby maintaining the stakes inserted into the pockets in an upright position.

15. A pocket-body or plate provided with a stake-pocket on one side, said pocket having inclosing walls for the stake opposite the upper terminal of the plate, and a bunk pocket or cavity disposed on the opposite

side of the plate opposite the stake-inclosing walls aforesaid.

16. In combination with a car sill, a plate provided with an open top bunk-pocket overhanging the sill and facing the inside of the car, and provided with a stake-pocket 55 opposite to and partitioned from the bunk pocket and facing outwardly or away from the car.

17. In combination with a car side sill, a pocket-body provided with a bunk-pocket or 60 open top receptacle resting on the sill and facing toward the inside of the car.

18. In combination with a car side sill, a pocket-body provided with a bunk-pocket or receptacle supported on the sill, means 65 for securing the pocket-body to the sill, a stake-pocket opposite the bunk pocket, tension members leading from the pocket-body across the car and above the sill, and means on the opposite side of the car for anchoring 70 the opposite ends of the tension members.

19. In combination with the side sills of a car, pocket-bodies secured to the sills on opposite sides of the car, and disposed opposite one another transversely across the car, and projecting a suitable distance above the sills, means for securing the pocket-bodies to the sills, and cross-tension members or ties 75 above the sills for connecting together the upper portions of oppositely disposed pocket-bodies for maintaining the axes of the pockets in vertical planes and the stakes inserted thereinto in an upright position.

20. In combination with a pocket-body 85 provided with a depression on one side, a detachable complementary member shouldered to the pocket-body and operating to form with the walls of said depression a passage or open-bottomed pocket for receiving a stake.

In testimony whereof I affix my signature, in presence of two witnesses.

KENNETH ROSS.
